UNITED STATES PATENT OFFICE.

JAMES SCOTT PARRISH, OF RICHMOND, VIRGINIA, ASSIGNOR TO RICHMOND CEDAR WORKS, OF RICHMOND, VIRGINIA, A CORPORATION OF VIRGINIA.

ICE-CREAM FREEZER.

1,144,687.

Specification of Letters Patent. Patented June 29, 1915.

Application filed February 9, 1911. Serial No. 807,653.

To all whom it may concern:

Be it known that I, JAMES SCOTT PARRISH, a citizen of the United States, and a resident of Richmond, county of Henrico, and State of Virginia, have invented certain new and useful Improvements in Ice-Cream Freezers, of which the following is a full and clear specification, reference being had to the accompanying drawings, in which—

10 Figure 1 is a perspective view with the dome of the gearing separated a short distance from the frame; and Fig. 2 a vertical longitudinal sectional view showing the frame applied to a tub.

15 The object of this invention is to provide an ice cream freezer gearing frame of the type covered by patent to Rollman No. 1,011,247, dated Dec. 12, 1911, and the invention consists in certain novel features of 20 construction hereinafter set forth.

The frame consists of a metal ring *a* constructed of a flat bar set on edge and connected across its center with a transverse gear-supporting bar *b*; this bar or plate *b* being provided with a supplemental plate *c* riveted to its under side to receive the upper cylindrical end of the ice cream can top *a*. The bar *b* has its ends upturned and riveted to the inner face of the ring. The ring *a* is 30 made in two semi-circular parts, and the abutting ends of these two parts are locked rigidly together by the ends of the cross bar or plate *b*.

Projecting from opposite vertical flat 35 sides of the ring *a* is a pair of parallel bars *e* set vertically edge-wise and formed integral with the ring. At one end one or both of these bars may be provided with an opening *f* for the reception of the frame-locking hook carried by the tub, and between the bars may be integrally forged a transverse 40 bracing plate *g*. At the other end of the frame may be forged a transverse plate *h* which serves as one of the hinge members, 45 this plate being provided with openings *i* for the reception of the hooks on the tub clip *j*. This plate *h* and the adjacent wall of the ring *a* are provided with holes *k* for the reception of the drive shaft *l* of the 50 gearing.

The dome *m* of the gear casing has its depending flange *n* fitted to the upper edge of the ring *a*; this flange lying within the ring or on the outside thereof, as may be desired, suitable rivet holes *o* being provided in the 55 flange and the ring to enable the dome to be fastened rigidly to the ring. When the dome is thus fastened to the ring, it serves to brace the same and this bracing function is especially valuable in view of the fact 60 that the ring is made in two parts. It will be observed that with the construction above described, the frame bars *e* may be forged integral with the ring, and the ring together with the dome will form a complete casing 65 for the gearing.

Having thus described my invention, what I claim as new and desire to secure by Letters Patent, is—

1. A frame for ice cream freezer gearings, 70 consisting of a ring-shaped flat bar set vertically on edge and constructed of two sections, a transverse bar extending across the ring and fastened to the inner face thereof across the joints between said sections, a 75 pair of flat bars projecting from each of said sections and having their outer ends connected by transverse cross bars, and a dome whose lower edge is fastened to and embraces the upper edge of said ring-shaped 80 flat bar.

2. A frame for ice cream freezer gearings, 85 consisting of a ring shaped flat bar set vertically on edge and constructed of two sections, a transverse bar extending across the ring and fastened to the inner face thereof across the joints between the sections, and a pair of flat bars projecting from each of said sections and having their outer ends connected by transverse integral cross bars, 90 for the purpose set forth.

In testimony whereof I hereunto affix my signature in the presence of two witnesses.

JAMES SCOTT PARRISH.
